UNITED STATES PATENT OFFICE

GRADY W. COBLE, OF GREENSBORO, NORTH CAROLINA.

RECEPACLE FOR HOLDING MATCHES, TOOTHPICKS, OR THE LIKE.

982,411.

Specification of Letters Patent. Patented Jan. 24, 1911.

Application filed May 7, 1910. Serial No. 560,017.

To all whom it may concern:

Be it known that I, GRADY W. COBLE, a citizen of Greensboro, in the county of Guilford and State of North Carolina, have 5 invented certain new and useful Improvements in Receptacles for Holding Matches, Toothpicks, or the Like; and I do hereby declare the following to be a full, clear, and exact description of the same, reference 10 being had to the accompanying drawings, forming a part of this specification, and to the figures and letters of reference marked thereon.

This invention relates to improvements 15 in receptacles for holding matches, toothpicks, etc., the object being to provide a receptacle from which a limited number only of the contained articles may be removed at a time, thus rendering the box or 20 receptacle particularly well adapted for use in public places.

To these ends the invention consists in certain novel details of construction and combinations and arrangements of parts, all 25 as will be now described and the particular features of novelty pointed out in the appended claim.

In the accompanying drawings, wherein is illustrated the preferred embodiment of 30 the invention—Figure 1 is a perspective view of a receptacle constructed in accordance with the present invention. Fig. 2 is a cross-sectional view. Fig. 3 is a top plan view.

35 Similar letters of reference in the several figures indicate the same parts.

Referring to the drawings, the box consists of the panels or side pieces A suitably joined together forming a rectangular cas- 40 ing having a bottom B. This bottom piece B is preferably removably connected with the body portion in any suitable or pre-ferred manner, in the present form illus-trated the bottom being shown as a slide.

45 Extending inwardly and downwardly from the top of the side pieces A are panels or sections C, shaped as shown and con-nected at their meeting edges and forming

a hopper like top for the box having an opening D at the bottom thereof. The 50 panels C it will be noted do not extend to the bottom of the box (see Fig. 2) a suffi-cient space being left to permit the passage of the articles contained in the box into the space below the opening in the hopper top, 55 as will hereinafter be explained.

The width of the opening D at the bot-tom of the hopper like top in both direc-tions is slightly greater than the length of the articles contained in the box. In filling 60 the box the bottom is removed, the box in-verted and the articles placed in the box filling the space between the walls of the hopper like top and sides of the box. When turned right side up a slight shake 65 of the box will cause a few of the articles to pass to the space below the opening at the bottom of the hopper shaped top. It will thus be seen that only the articles at this opening can be withdrawn, thus pre-70 venting waste and extravagant use of the articles.

It will, of course, be understood that the receptacle may be made of any suitable or preferred material and could be of different 75 shape from that illustrated without depart-ing from the spirit of the invention.

Having thus described my invention, what I claim as new and desire to secure by Let-ters Patent of the United States is— 80

In a box or receptacle, the combination with the sides, of the removable bottom, the top having inwardly and downwardly in-clined panels fixed at the top to said sides and having an opening at the bottom there-85 of, the lower edges of the walls of the top extending to within such distance of the bottom of the box as to permit the passage of a single layer only of the articles held between the top and sides of the box into 90 position to be withdrawn through the open-ing in the top of the box.

GRADY W. COBLE.
